(57) **CLAIM**

The ornamental design for a bottle dispenser adapter, as shown and described.

DESCRIPTION

FIG. 1 is a top perspective view of a bottle dispenser adapter showing my new design;

FIG. 2 is a bottom perspective view thereof;

FIG. 3 is a top perspective view thereof shown connecting to a bottle and a spray dispenser;

FIG. 4 is a front elevational thereof, the rear elevational view being a mirror image thereof;

FIG. 5 is a right side elevational thereof, the left side elevational view being a mirror image thereof;

FIG. 6 is a top plan view thereof; and,

FIG. 7 is a bottom plan view thereof.

In the drawings, the broken lines show portions of a bottle dispenser adapter that form no part of the claim; In FIG. 3, the broken lines also depict a bottle and spray dispenser that form no part thereof.
